(57) **CLAIM**

The ornamental design for a hanging lamp, as shown and described.

DESCRIPTION

FIG. 1 is a perspective view of a first embodiment of the invention.

FIG. 2 is a right side elevation view of FIG. 1.

FIG. 3 is a front elevation view of FIG. 1.

FIG. 4 is a left side elevation view of FIG. 1.

FIG. 5 is a rear elevation view of FIG. 1.

FIG. 6 is a top plan view of FIG. 1

FIG. 7 is a bottom plan view of FIG. 1

FIG. 8 is a perspective view of a second embodiment of the invention.

FIG. 9 is a right side elevation view of FIG. 8.

FIG. 10 is a front elevation view of FIG. 8.

FIG. 11 is a left side elevation view of FIG. 8.

FIG. 12 is a rear elevation view of FIG. 8.

FIG. 13 is a top plan view of FIG. 8; and,

FIG. 14 is a bottom plan view of FIG. 8.

The dashed lines in FIGS. 1-14 are for illustrative purposes only and form no part of the claimed design.
